DESIGN FOR A SPRAY GUN OR THE LIKE

Glenn W. Tammen, Chicago, Ill., assignor to Binks Manufacturing Company, Chicago, Ill.,
a corporation of Delaware

Application July 2, 1938, Serial No. 78,238

Term of patent 7 years

To all whom it may concern:

Be it known that I, Glenn W. Tammen, a citizen of the United States and residing at Chicago, county of Cook and State of Illinois, have invented a new, original, and ornamental Design for a Spray Gun or the like, of which the following is a specification, reference being made to the accompanying drawings, forming a part thereof.

Fig. 1 is a top plan view of a spray gun or the like, showing my new design;

Fig. 2 is a side elevational view of the same;
Fig. 3 is a front end elevational view of the same; and

Fig. 4 is a rear end elevational view of the same.
I claim:

The ornamental design for a spray gun or the like, substantially as shown.

GLENN W. TAMMEN.
